UNITED STATES PATENT OFFICE.

RAPHAEL JACOBUCCI, OF PROVIDENCE, RHODE ISLAND.

PRINTING PRESS.

Application filed November 1, 1922. Serial No. 593,407.

To all whom it may concern:

Be it known that I, RAPHAEL JACOBUCCI, a citizen of the United States, residing at Providence, in the county of Providence and State of Rhode Island, have invented certain new and useful Improvements in Printing Presses; and I do hereby declare the following to be a full, clear, and exact description of the invention, such as will 10 enable others skilled in the art to which it appertains to make and use the same.

This invention relates to multicolor printing and particularly to presses of this type adapted to print on webs and to cut the 15 printed web into sheets.

The object of the present invention is to render presses of this type flexible and efficient,—adapted to make successive color impressions with accuracy and rapidity.

20 The invention consists in the novel construction, arrangement and combination of parts as hereinafter more particularly described and claimed.

Four sheets of drawings accompany this 25 specification as part thereof in which like reference characters indicate similar parts throughout.

Figure 1 is a front elevation of a machine embodying the present invention;

30 Fig. 2 is a side elevation taken from the left of Fig. 1;

Fig. 3 is a side elevation taken from the right of Fig. 1;

Fig. 4 is a top plan view;

35 Fig. 5 is a transverse sectional view through the upper part of the press;

Fig. 6 is a longitudinal section taken on line 6—6 of Fig. 5;

40 Fig. 7 is an enlarged cross-sectional view taken through the head of the press showing the platen type chase and adjustment members;

Fig. 8 is a cross-sectional view taken 45 through the head of the press illustrating the adjustable paper guides;

Fig. 9 is a cross-sectional view through the platen;

Fig. 10 is a fragmentary detail sectional view of the sub-base for the type chase;

50 Fig. 11 is a plan view of the type chase;

Fig. 12 is a side elevation of a platen;

Fig. 13 is a plan elevation of a platen;

Fig. 14 is a plan elevation of the type chase base, and,

Fig. 15 is a plan view of the type chase 55 sub-base.

In the embodiment illustrated, a frame 1 supports a horizontally disposed drive shaft 2 adapted to be operated by any suitable means, as electric motor 3, and carrying eccentrics adapted to operate connecting rods 4 to rock the type bed or chase carrier 5 which is pivoted to the frame as at 5' and extends longitudinally thereof. The weight of bed 5 is counterbalanced in whole 60 or in part by compression links 12 composed of members telescoping with a tube which houses a compression spring. The drive shaft 2 further carries an eccentric 65 adapted to operate a lever 7 through a connecting rod 6 to rock a secondary shaft 8, also extending horizontally and longitudinally of the press, said shaft 8 having levers 9 secured thereto which are connected by links 10 to an inking device 11 adapted to 70 slide transversely of the frame, and carrying the customary inking rollers 17 which are adapted to receive ink from a plurality of ink applicators 19 set in suitable detachable ink reservoirs 19^a. The reservoirs 19^a 75 are detachably secured to the frame by means of the bolts 200, as best illustrated in Fig. 5 of the drawings. Ink spreading disks 18 of the customary character which may be rotated step by step by any suitable mechanism known in the art are disposed in the path of the inking rollers between the type and the ink reservoirs.

80 A platen-carrying head 13 is supported by frame 1 longitudinally thereof and above the type-bearing bed 5 and is preferably of a reinforced construction having a medial longitudinal rib 20 and a plurality of transverse ribs 21, at the intersection of which, at suitable spaced distances, are 85 bosses 22 having suitable orifices to receive bolts 23 adapted to secure the platens 24 in position. Each platen 24 has a central threaded socket 25 adapted to receive bolt 23 and is provided adjacent its opposite parallel edges with grooves 26 so that a suitable sheet pad 27 can be passed over the face of the platen and be secured there-to by strips 28 forced into the grooves 26 90 confining the sheet as illustrated in Fig. 9. 105

Intermediate the platens 24 in the head 13 are transversely adjustable paper guides 57—57' each having a paper-receiving

groove 59, the grooves in guides 57 facing those in guides 57'. Each guide has laterally extending lugs 58 adapted to slidably seat in similar grooves 56 provided at 5 the base of the transverse guiding grooves 55 within which the guides slide (see Figs. 6 and 8). At the top of each of the grooves 55 is a member 60 having prongs 61 adapted to engage an annular groove formed in a 10 screw 63 having right and left handed threads 62 and 62' respectively on opposite sides of said groove, said screw threaded portions engaging right and left hand threaded orifices in the guide members 15 57-57'. By the rotation of screw 63 it will be apparent that guide members 57-57' can be either advanced simultaneously toward each other or moved apart as desired to adjust the press to receive and guide paper of 20 varying widths.

The type chase 46 is provided upon its rear edge with an outstanding lug 47 and upon its front edge with a beveled cam face 45; and upon one side of each chase is a 25 type-high gage bar 48 having downwardly projecting pins 50 adapted to seat in suitable co-mating orifices in the chase, over compression springs 49 that maintain bar 48 in a normally elevated position level with 30 the type faces.

The ends of gage bars 48 extend beyond the front and rear of the chases and incline downward slightly to make easy approach for the ink rolls. Above the ends 35 of said bars on the frame member 13 are stop abutments 48^a with which the ends of said bars engage when the bed rises to make an impression, thus pushing the bars downward relatively below the type faces so that 40 the upper surface of the bars 48 do not press upon the paper and make ink impressions of their upper surfaces upon the paper.

A base 41 is provided upon which the 45 type chase is adapted to be seated, said base having an upward and inward directed securing member 42 under which the outward turned lug 47 of the chase is adapted to engage. The base 41 is equipped, upon its 50 front edge, with a bracket 43 adapted to pivotally support a cam lever 44 operative to press upon cam face 45 of the type chase to securely lock the latter in position upon the base 41. The base 41 is adjustably seated upon a sub-base 32.

The sub-base 32 is provided upon its lower face with a dovetailed guide-rib adapted to fit in a resilient dovetailed guide-member 30, which, in turn, rests in a 55 suitable slide way provided in the type bed 5. The resilient dovetailed member 30 is compressible upon the sub-base 32 by means of a bolt 31 threaded through bed 5 as is well illustrated in Fig. 7. The sub-base 32 is further provided adjacent each of its four

corners with vertically disposed adjustment members 33 which have exterior threads adapted to co-act with interiorly threaded orifices formed for the purpose in the sub-base (see Fig. 10). The adjustment members 33 may be formed with spherical bearing ends 34 upon which the base 41 is adapted to bear. For operative purposes said members 33 are reduced between their ends and provided with spiral teeth of such pitch 70 as to co-mate with the usual threads of bolts 36 arranged at right angles to the axis of adjustment members 33 in a suitable orifice provided therefor in the sub-base 32. The transverse screws 36 have enlarged parts 37 75 in which are formed annular grooves 38 adapted to co-operate with screws or pins 39 to prevent longitudinal movement of said screws 36. Heads 40 enable screws 36 to be rotated to, in turn, rotate adjustment members 33 to raise or lower the latter and adjust the chase bases. As indicated in Fig. 15 the rear adjustment members 33 are associated with operating screws extending 80 forward and are adjustable from the front 85 of the machine.

Brackets 14 at one end of the frame 1 sustain a roll of paper 14^a, a paper guide roll 14^b and a stock weight 14^c which is pivoted to said bracket for the purpose of 90 applying suitable retarding friction to the outer layer of paper as the roll unwinds.

In order to provide for feeding a web of paper intermittently, causing the feed to stop during each printing impression and 100 then advance a measured distance to receive the next impression, intermittently operated flanged feed rolls 16, 16^a are disposed at that end of frame 1 that is opposite the roll-holding bracket 14, the flanges of the 105 feed rolls gripping the opposite margins of the web.

Cutting mechanism, indicated as a whole by reference character 15, operates at regular intervals to cut off in succession printed sheets of dimensions determined by the feed 110 adjustment of the feed mechanism. A cut is made at each non-feed period.

In order to rotate the feed rolls intermittently in proper timing with the operation of the printing mechanism, the lower roll 16 is rotated by the mechanism to be now described: Secured on shaft 2, at the left hand end (as viewed in Fig. 1), is a cam 80 having a cam groove 81 in which engages a stud on a lever 82 that is pivoted at one end on frame 1; to the other end of lever 82 there is pivoted a link 83. A rack 84 is slidably mounted in the frame, the lower end of said rack being pivotally connected to the upper end 115 of link 83. The continued rotation of shaft 2, therefore imparts reciprocating movements (separated by periods of dwell) to rack 84. Concentrically mounted with respect to the axis of lower feed roll 16 is a 120

areas than on the others. To equalize the pressure of the ink rolls on the types, the gage bars 48, which extend exactly type high, receive the pressure of the rolls and prevent the smaller area of type from sinking into the rolls more than do the larger areas. At each impression the feed rolls 16, 16* stop, and the cutter cuts off a sheet; between impressions the feed rolls advance 10 the web a distance equal to that between centers of the several chases or to any pre-determined extent suitable to make the several color impressions or color impression and embossments according to the pre-determined design of the printer. The several sub-bases may be adjusted toward or from each other as required or a greater or less number may be secured to the bed and the associated mechanisms adjusted or applied accordingly.

Having thus fully described my invention, I claim:

1. A printing press comprising a frame, a head fixed on said frame carrying a plurality of downward facing platens, a type bed carrying chase bases, means for leveling said chase bases with respect to type bed, paper guides interposed between adjacent platens and carried by the head, inking devices, means for operating the type bed and inking devices, and means for feeding the paper intermittently substantially as specified.

2. A printing press comprising a frame, a head fixed on said frame carrying a plurality of downward facing platens, a type bed pivotally supported on the frame carrying a plurality of chase bases, paper guides on the head interposed between adjacent platens, means for simultaneously adjusting said guides transversely of the frame to vary the space therebetween, inking devices, means for operating the type bed, and means for feeding the paper intermittently substantially as specified.

3. A printing press comprising a frame, a head fixed on said frame carrying a plurality of downward facing platens, a type bed carrying a plurality of chase bases, paper guides on said head interposed between adjacent platens, right and left hand screws for simultaneously adjusting said guides transversely of the frame to vary the space there-between and center the paper, inking devices, means for operating the type bed and inking devices and means for feeding the paper substantially as specified.

4. In a printing press having a fixed platen-carrying head, a type bed and means for moving it toward and from the platens, means for feeding paper between said platen carrying head and type bed, guides on said head for said paper having opposing grooves adapted to receive the edges of the paper, and means for simultaneously

adjusting said guides equally toward or away from each other.

5. In a printing press a type-chase, a removable base for said chase, locking means for securing the chase to the base, a sub-base, means carried by the sub-base for leveling the base thereon and means for removably securing the sub-base to the frame of the press.

6. In a printing press a type-chase, a removable base for said chase, locking means for securing the chase to the base, a sub-base, means carried by the sub-base for leveling the base thereon comprising exteriorly threaded leveling posts having annular grooves provided with spiral teeth adapted to co-mate with exteriorly threaded adjustment screws and said adjustment screws arranged transversely of the posts and secured in the sub-base so as to permit their rotation but prevent any longitudinal movement thereof, and means for removably securing the sub-base to the frame of the press.

7. In a printing press, the combination of a printing bed adapted to support type thereon, a platen, an inking mechanism including an inking roll adapted to move over the type surfaces, a gage bar, elastic means for maintaining the surface of said gage bar at type face level, and means on the platen adapted to contact with the gage bar and depress it below the type faces, when a printing impression is made.

8. In a printing press, a platen, a type-carrying bed, means for causing relative movement between them to effect printing impressions, an elastically yieldable gage bar held on the bed with its surface at type level, and having projecting ends, an inking mechanism including an inking roller, stops associated with the platen adapted to engage the projecting ends of said gage bar when a printing impression is made and depress the gage bar below the type surface.

9. In a multicolor printing press, a frame, a platen support, a bed, means thereon for receiving a plurality of groups of type in alinement, a plurality of ink supply devices, and inking means adapted to supply ink from a selected supply device to a selected type group, means for intermittently feeding a web between the bed and platen over said several type groups, and means for causing relative movements of said platen and bed toward and from each other.

10. In a multicolor printing press, a frame, a platen support, a bed, means on the bed for receiving a plurality of groups of type in alinement, means for moving said bed and platen support relatively to each other to print, inking rolls movable over the bed, a plurality of removable ink spreading devices in the path of movement of said rolls for spreading ink upon the rolls, and

gear wheel 85, the teeth of which engage with the teeth of rack 84. The gear wheel 85 is free to rotate with respect to feed roll 16 except as it is connected therewith intermittently by a ratchet and pawl device. A pawl 86 is pivoted to one face of said gear wheel 85, and this pawl has a normal tendency to engage a ratchet wheel 87 fast to roll 16. An angularly adjustable shield 88 10 on a handle member 89 is interposed between the pawl 86 and ratchet 87, so that as the gear 85 oscillates back and forth, the said shield allows the pawl to engage the ratchet during a portion of the oscillation determined by the angular position of the shield. Graduation marks may be applied to the shield on handle and frame so that the amount of rotary movement to be imparted to the feed wheel 16 can be accurately measured and predetermined. The rack actuates the feed on its upward movement.

While the feed is stationary,—that is, during the downward movement of rack 84,—the cutting mechanism is operated to sever 25 a printed sheet or card. The cutting mechanism comprises the elements now to be described. A knife bracket 90 is rigidly secured to the frame to the left of the machine (as viewed in Fig. 1) and outside of the feed 30 rolls. This bracket is suitably offset from the frame 1 and has a guide way in its outer face,—the face away from the frame 1,—in which a knife carrying slide 91 is adapted to be reciprocated. To the knife carrying slide 35 91 a movable knife 92 is secured. Said knife 92 has an edge 93 adapted to sever the paper with a draw cut. Bolted to the upper edge of bracket 90 is a fixed or ledger blade 94 across the edge of which the paper is sheared 40 by the obliquely disposed edge of knife 92. Suitably fulcrumed at 95 on frame 1 is a knife operating lever 96, of the first order, pivoted at 97 to the lower end of knife carrying slide 91. Bracket 90 is so formed as to 45 provide an open space between its edges at the lower end in order to permit free oscillation of lever 96. Mounted on rack 84, as shown in Fig. 2, is a dog 98 so disposed that it strikes the free end of lever 96 on the 50 downward stroke of the rack, thus elevating the knife 92 and severing a sheet while the feed rolls are at rest. The dog 98 may be removed or turned out of operative position in case it is not desired to sever sheets from 55 the web being printed.

Numeral 100 indicates a pressure release lever whereby the bed may be moved slightly from the platens in case of need even though the bed be pressed against the platens by the 60 operating cams and connecting rods 4. Numeral 101 indicates a handwheel by means of which the shaft 2 may be rotated or rocked by hand.

In order to stop the machine in case the 65 web should break or upon exhaustion of the

paper an automatic mechanism is provided as follows:

A feeler plate 102 is disposed at the end of frame at which the paper enters; said plate 102 rests horizontally with its upper 70 surface substantially tangent to, or, it may be, a little higher than the surface of idle roll 14^b. Slots 103 are formed through feeler plate 102. A feeler arm 104 is pivoted at 75 105. The free end of arm 104 is equipped with a feeler 106 consisting of elastic fingers disposed over slots 103 and adapted to bear upon the paper passing between them and the feeler plate. The feeler 106 is curved in the direction indicated in Fig. 1. 80 Should the paper break between the feeler and supply roll, or the supply cease, arm 104 would drop by gravity, the elastic fingers of the feeler entering the slots 103. An automatic trip lever 107 is engaged by arm 85 104 and held when the paper is feeding normally with its abutment end 108 engaging the end of a spring actuated trip rod 109 that is slidable in a guide bearing 110 and is normally urged elastically upward by a 90 coil compression spring 111, that bears against the upper side of said guide bearing and a collar 112 on the rod. A stop collar 113 limits the upward movement of the rod. At its lower end trip rod 109 is connected to 95 a bell crank lever 114 the end 115 of which may serve as a trip dog to actuate a switch (not shown) or any kind of stop mechanism to stop the operation of the machine.

In operation a roll of paper is mounted 100 on bracket 14 the end thereof passed over idle roll 14^b and the stock weight 14^c adjusted to keep the paper smooth on roll 14^a as it is being unwound. The end of the paper web is passed over feeler plate 102 105 beneath the feeler 106 and the web is passed along between the bed and platens, the guides 57, 57' having been adjusted so that the edges of the web enter the guide notches 59 therein. Said guides serve to 110 center the web properly with respect to the type bed. The web is then passed between the flanges of feed rollers 16, 16^a and under the ledger blade 94. Types are locked in the various chases on the type bed in accordance with the number of colors to be 115 used or whether the work is to be embossed. If an embossing impression is to be made a selected ink spreader and reservoir will be removed and, preferably, ink rollers fitted to 120 such length that they do not pass over the embossing type. The ink reservoirs 19 will be filled, respectively, with the selected colored inks. Each color of ink will, as is obvious, be spread over that portion of the 125 inking rolls appropriate to the type selected for that particular color. It may happen that one chase will embrace a much smaller type area than others, whereby a heavier ink impression is likely on the smaller type 130

detachable and adjustable ink supplying reservoirs adapted to deliver ink to said rolls.

11. In a printing press, a frame, a platen support, a bed, means for producing movement thereof to print, means for feeding a web of paper between the bed and platen, said means including a reciprocating bar and

means operated thereby on one stroke for advancing the paper, cutting means for severing a printed sheet from the web, and means on said bar arranged to co-operate on its other stroke with said cutting means to sever the sheet.

In testimony whereof I affix my signature.

RAPHAEL JACOBUCCI.
